UNITED STATES PATENT OFFICE.

PURDY M. RANDALL, OF NEW YORK, N. Y., ASSIGNOR, BY MESNE ASSIGNMENTS, TO
FRANK C. BRIGGS, TRUSTEE, OF NEW YORK, N. Y.

COMMUTATOR.

Application filed April 14, 1919, Serial No. 289,902. Renewed January 27, 1922. Serial No. 532,260.

This invention has relation to commutators for the distribution of electric current, with particular reference to a commutator for use in motor vehicles, and has for its 5 specific object to provide a commutator of a new and novel type designed to replace the commutator at present used upon a popular low priced car with a view to improving the general efficiency and operation of the 10 vehicle.

A particular object of the invention is to provide a commutator which is reversible so that when the contacts exposed at one side thereof become worn through use, the 15 commutator may be reversed to present a new surface and in this manner secure double service from a single device.

The commutator comprises a disk with a 20 flange encircling the same, of fibre or other insulating materials, having contacts extending through the disk presenting opposite surfaces for engagement with a brush upon the timer shaft.

In addition to the foregoing, this invention 25 comprehends improvements in the details of construction and arrangement of parts, to be hereinafter described and particularly set forth in the appended claims.

In the accompanying drawings in which 30 similar and corresponding parts are designated by the same characters of reference throughout the several views in which they appear,

Figure 1 is a face view of my improved 35 commutator illustrating parts in section.

Figure 2 is a longitudinal section taken through the commutator.

Figure 3 is a view thereof in plan.

Figure 4 is a face view of the commutator 40 with working parts removed.

Figure 5 is a face view of the brush holder, and

Figure 6 is a view thereof in side elevation with parts broken away.

With reference to the drawings, in which I have illustrated the preferred embodiment of my invention, 10 indicates a disk of fibre or other non-conducting material having its center portion formed with a circular perforation 11, and opposite faces preferably formed with concentric grooves 12. Enclosing the disk and engaging the periphery thereof is a band 13 of fibre or other nonconducting material having its ends extended beyond the surfaces of the disk 10 as shown in Figure 2, the inner end of the flange serving to seat the commutator against the base plate. Extending transversely through the disk 10 and located in perforations provided therein are contact bars 14 formed of sections of good conducting material such as copper rod preferably circular in cross section. It will be noted from Figure 2 that the ends of the contact sections 14 are exposed at opposite sides 60 of the disk. To provide a path for the current from the contact bars 14 I provide radially extending openings through the band 13 and disk 10 at points opposite the contact bars in which perforations I insert short sections of rod 15 which enter at one end into recesses 16 in the contact bar 14 and at their opposite ends are formed with conical recesses 17. The outer ends of the rods 15 preferably flush with the periphery 70 of the disk 10 so that said disk may be disengaged from the band if desired. This makes it possible to reverse the disk without reversing the band, though it is simpler to 75 reverse both as a unit. In this connection 80 it will be observed that the band or flange 13 preferably projects equally at both sides of the disk. The radial openings in the band 13 are threaded to receive machine screws 18 which are pointed at their inner 85 ends to enter recesses 17 in the outer ends of the rods 15, and jamb nuts 19 applied to their opposite ends to bind against the outer surface of the band 13 and to secure the screws in place. Thus, the screws 18 serve as binding posts to which the leads from the several spark plugs may be connected. The timer shaft indicated at 20 is formed with the reduced portion 21 which passes through the central aperture 11 of the commutator, and the timer shaft is formed with a further reduced and threaded portion 22 upon which I mount a collar 23 in threaded engagement shown in Figures 5 and 6. One end of the collar is notched at opposite sides 95 as at 24 to receive a pin 25 which extends through a transverse opening in the reduced portion 22 of the timer shaft to securely lock the collar in place. A recessed collar 26 may then be applied to the reduced portion 100 105 22 to cover the ends of the collar and the ends of the pin 25 and a nut 27 may then be further applied to the reduced portion to secure the collar 26 in place. The collar 26 forms a part of the conventional construc- 110

tion of commutator at present used in the vehicle in which my improved commutator is designed to be embodied. The collar 23 is formed with a radially extending lug 28 which is apertured transversely to receive the reduced end 29 of a brush device comprising an angularly bent rod 30 having the reduced portion 29 at one end and its opposite end provided with a threaded aperture 31 in which to receive the reduced and threaded end 32 of a block 33 of good conducting material such as copper. A coiled spring 34 surrounds one portion of the rod 30 with one end bearing against the lug 28 and the other upon the rod 30 to urge the block 33 into engagement with the face of the disk 10 and consequently ensure firm contact between said block 33 and the contact bars 14 during rotation of the timer shaft. The commutator is rendered dust proof by applying a cap 35, preferably imperforate and conical in form, thereto having a radial flange 36 on its base portion extending outwardly to engage the outer face of the disk 10 and to snugly fit within the band 13. The apex of the cover 35 is formed with a depression 37 in which is received a spring finger (not shown) forming a part of the equipment of the vehicle, to secure the cap 35 in place. This cap 35 may be pressed of thin metal. In order to rotate the timer to secure advancement or retardation of its spark I provide a device consisting of a plate 38 curved to fit the outer surface of the band 10 and having transversely extending notches 39 formed therein on one margin, and an outwardly and radially extending apertured lug 40 to which the rod leading from the spark lever may be attached. A pair of machine screws 41 are threadedly engaged in radial openings in the band 13 and enter the notches 39 when the plate 38 is in place. By tightening up the screws the plate is securely held. It will be obvious, that during rotation of the timer shaft the copper block 33 will successively engage the ends of the bars 14 to distribute current successively to the rods 15 and binding posts and thence to the spark plugs. The fibre or material from which the disk 10 is composed is designed to wear approximately at the same rate as the wear of the contacts 14. Any dust or particles that may accumulate as the result of operation of the timer will be thrown outward and collected in the groove 12 for which purpose it is provided. However, should one side of the commutator be unduly worn so as to reduce the efficiency of operation thereof it becomes a simple matter to remove the nut 27, band 26 and collar 23 whereupon the commutator as an entirety may be removed from the timer shaft, reversed, and reapplied presenting the opposite side of the disk end outward. The

several working parts may then be replaced upon the timer shaft and a new surface will be presented. In this manner one device will give double the length of service of any other commutator of a similar kind at present in use. It will also be obvious that the block 33 of the brush may be readily removed when worn and a new one substituted. When the commutator is reversed as described above, the plate 38 may be readily withdrawn from beneath the screws 41, reversed and reapplied on the other side in an obvious way.

By providing contacts on the side of the commutator away from the main body of the shaft which it surrounds and which is subjected to the oil and grease from the engine, and by providing a readily removable dust cap surrounding the working faces of the contact and the brush which engages the same, the working parts of the commutators are kept away from the oil, grease and dirt of the engine. The wiping contact continually keeps the working faces of the stationary contacts clean and no oil is necessary in the operation of the device.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:

1. A commutator for internal combustion engine including a support of non-conducting material adapted to be mounted about a timer shaft, contacts at both sides of the support, and a rotor having a single contact adapted to be mounted upon the timer shaft and to successively engage one set or the other of the contacts of the support depending upon which side of the support is disposed adjacent the rotor.

2. A commutator including a disk of non-conducting material adapted to be mounted about a timer shaft, contacts extending transversely through the disk exposing opposite ends whereby either side of the disk may be presented for use, and a brush adapted to be mounted upon the timer shaft to engage the contacts.

3. In a commutator, a disk of non-conducting material adapted to be mounted about a timer shaft, bars of conducting material extending transversely through the disk and having opposite ends exposed and a brush adapted to be mounted upon the timer shaft to successively engage the contact bars, said disk being reversible end to end.

end to present either face thereof for engagement with the brush.

4. In a commutator, a disk adapted to be mounted about a timer shaft and having its opposite faces grooved concentrically, metallic bars extending transversely through the disk exposing opposite ends, and a brush adapted to be mounted upon the timer shaft and to successively engage the contact bars during rotation of the timer shaft.

5. In a commutator, a disk of non-conducting material, contacting members therein, a band of non-conducting material surrounding the periphery of the disk, conducting rods extending radially through the disk in engagement with the members, and second contact rods extending through the band and engaging the outer ends of the first rods.

20 6. In a commutator, a disk of non-conducting material, contact members located therein, conducting members extending radially into the disk having their inner ends contacting the contacts and their outer ends flush with the outer periphery of the disk, a band of non-conducting material surrounding the periphery of the disk and having openings registering with the contact members and threaded members inserted in said opening and engaging the conducting members forming binding posts therefor.

35 7. A commutator including a disk of non-conducting material, a band of non-conducting material surrounding the periphery of the disk and extending beyond the faces thereof, contacts mounted in the disk, and a removable cap to cover one face of the disk and to be enclosed within the band.

40 8. In a commutator, a disk of non-conducting material, contacts mounted therein, a band of non-conducting material surrounding the periphery of the disk and extending beyond the faces thereof, and a conical cap having an outwardly extending radial flange on its face portion adapted to engage either face of the disk and to be enclosed within the band.

45 9. A commutator including a reversible disk of non-conducting material, a band of non-conducting material surrounding the periphery of the disk and extending equally at both sides beyond the faces thereof, contacts mounted in the disk and exposed at both sides, and a removable cap to cover one face of the disk and to be enclosed within either projecting portion of the band.

50 10. In a commutator, a body portion of non-conducting material, contacts mounted therein, a collar adapted to be mounted upon the timer shaft, an apertured lug extending therefrom, an angular arm pivotally mounted in the lug, a brush carried by the opposite end of the arm, and a coiled spring surrounding the arm to urge the latter and brush into engagement with the contacts.

11. In a commutator, a body comprising a disk of non-conducting material, contacts extending therethrough presenting opposite faces whereby the commutator may be reversed end to end to employ either side, and a lug mounted upon the periphery of the body, detachable and reversible with respect to the body so as to preserve its position when the commutator is reversed.

12. In a commutator, a disk of non-conducting material, a band surrounding the periphery of the disk, contacts in the disk extending therethrough to present opposite faces whereby the commutator may be reversed to employ either side, threaded members extending radially from the band, a plate having notches at one margin to receive the threaded members, a lug extending from said plate for connection to the sparking lever connection, said plate being removable for reversal when the commutator is reversed.

13. A timer comprising an insulating member fixed in position during normal operation, a series of contacts extending through said insulating member and terminating flush with the lateral surfaces thereof, means for reversibly securing said insulating member in position, and a rotatable brush adapted to engage the contacts on either surface of said member depending upon its position.

14. A timer comprising an insulating member fixed in position during normal operation and provided with a central opening, a series of contacts concentrically arranged about said openings and extending through said insulating member and terminating flush with the lateral surfaces of said member, means for reversibly securing said member in position, and a rotatable brush adapted to engage the contacts on either surface of said member depending upon its position.

15. A circuit maker and breaker for ignition circuits for gas engines comprising rotor and stator members, one of said members having similar, opposite, contact faces, and means for supporting said member so that either of said faces may be in operative relation to the other member.

16. A circuit maker and breaker for ignition circuits for gas engines comprising a ring-form reversible stator having similar opposite contact faces, and a brush carrying rotor.

17. In a timer for internal combustion engines, a commutator formed as a disc of insulating material and having spaced plugs extending therethrough, the ends of the plugs being flush with the respective faces of the commutator.

In testimony whereof I affix my signature.

PURDY M. RANDALL.
